DESIGN FOR A BRACELET

Otto Grun, New York, N. Y.

Application December 11, 1944, Serial No. 116,836

Term of patent 14 years

(Cl. D45—4)

To all whom it may concern:

Be it known that I, Otto Grun, a citizen of the United States, residing in the Borough of Manhattan, city, county, and State of New York, have invented a new, original, and ornamental Design for a Bracelet, of which the following is a specification, reference being had to the accompanying drawing, forming part thereof.

On the drawing,

Fig. 1 is a top plan view of a bracelet embodying my design;

Fig. 2 is a side elevational view of the bracelet shown in Fig. 1; and

Fig. 3 is a bottom plan view of the bracelet shown in Fig. 1.

I claim:

The ornamental design for a bracelet, as shown.

OTTO GRUN.
